CLAIM

The ornamental design for a curvature adjustable magnetic strut, as shown and described.

DESCRIPTION

FIG. 1 is a front, top and side perspective view of the curvature adjustable magnetic strut having five circular magnets located on a base plate;

FIG. 2 is a bottom view of the curvature adjustable magnetic strut of FIG. 1;

FIG. 3 is a top plan view of the curvature adjustable magnetic strut of FIG. 1;

FIG. 4 is a side elevational view of the curvature adjustable magnetic strut of FIG. 1;

FIG. 5 is an enlarged front view of the curvature adjustable magnetic strut of FIG. 1;

FIG. 6 is an enlarged rear view of the curvature adjustable magnetic strut of FIG. 1;

FIG. 7 is a top, front and side perspective view of the curvature adjustable magnetic strut of FIG. 1;

FIG. 8 is a bottom, front and side perspective view of the curvature adjustable magnetic strut of FIG. 1;

FIG. 9 is a bottom, front and side perspective view of the curvature adjustable magnetic strut of FIG. 1;

FIG. 10 is a bottom front and side perspective view of the curvature adjustable magnetic strut of FIG. 1;

FIG. 11 is a side elevational view of the curvature adjustable magnetic strut of FIG. 1;

FIG. 12 is a bottom view of the curvature adjustable magnetic strut of FIG. 1;

FIG. 13 is a perspective view of the curvature adjustable magnetic strut of FIG. 1;

FIG. 14 is a side and bottom perspective view of the curvature adjustable magnetic strut of FIG. 1;

FIG. 15 is a top, front and side perspective view of the curvature adjustable magnetic strut of FIG. 1 showing the base plate curved;

FIG. 16 is a bottom, front and side perspective view of the curvature adjustable magnetic strut of FIG. 15;

FIG. 17 is a side view of the curvature adjustable magnetic strut of FIG. 15;

FIG. 18 is a bottom view of the curvature adjustable magnetic strut of FIG. 15;

FIG. 19 is a top view of the curvature adjustable magnetic strut of FIG. 15;

FIG. 20 is an enlarged front view of the curvature adjustable magnetic strut of FIG. 15; and,

FIG. 21 is an enlarged rear view of the curvature adjustable magnetic strut of FIG. 15.
